UNITED STATES PATENT OFFICE.

CHARLES JACOB GUSTAFSON, OF CHATTANOOGA, TENNESSEE.

FORCE-FEED LUBRICATOR.

SPECIFICATION forming part of Letters Patent No. 784,788, dated March 14, 1905.

Application filed June 11, 1904. Serial No. 212,143.

To all whom it may concern:

Be it known that I, CHARLES JACOB GUSTAFSON, a citizen of the United States, residing at Chattanooga, in the county of Hamilton and State of Tennessee, have invented a new and useful Force-Feed Lubricator, of which the following is a specification.

The invention relates to force-feed lubricators, and has for its principal object to provide a novel means for forcing a lubricant into the oil-channels of journal-boxes and other portions of machinery, cars, and the like.

A further object of the invention is to provide a novel form of force-feed lubricator in which provision is made for discharging a predetermined quantity of oil to each portion of the device to be lubricated—as, for instance, in oiling the journals of mine-cars and other vehicles each of the journals will receive precisely the same quantity of lubricant.

A still further object of the invention is to provide a novel form of force-feed lubricator which may be attached to an ordinary form of oil-receptacle and readily carried about from place to place during the lubricating operation.

With these and other objects in view, as will more fully hereinafter appear, the invention consists in the novel construction and arrangement of parts hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the drawings, Figure 1 is a longitudinal sectional elevation of a force-feed lubricator constructed in accordance with the invention. Fig. 2 is a similar view of a portion of the same with the parts in different position. Fig. 3 is a transverse sectional elevation of a portion of the hollow plunger on the line 3 3 of Fig. 2.

Similar numerals of reference are employed to indicate corresponding parts throughout the several figures of the drawings.

The lubricator-receptacle 1 is in the form 50 of a metallic casing which preferably is provided with a handle 2 for convenience in carrying it from place to place, and in the upper portion of the receptacle is a filling-opening 3, which may be closed by a plug or 55 cap 4, the latter when in use being loosened or slightly unscrewed to permit the entrance of air to the interior of the casing to take the place of oil discharged therefrom. To the lower portion of one of the vertical walls 60 of the casing is secured the flange of the collar 5, internally threaded for the reception of the threaded portion of a cylindrical casing 6, that extends for some distance within the casing and has a projecting flange or collar 7 65 with a non-circular face for engagement by a wrench or similar tool for screwing the casing 6 into position. At the inner end of the casing 6 is an inturned flange 8, having a valve-seat 9, against which fits a disk valve 70 10, normally held to its seat by a coiled compression-spring 11.

Arranged within the cylindrical casing 6 is a loosely-fitting plunger 12, having at its inner end an annular flange 13, that is provided 75 with a plurality of notches or recesses 14 in order to permit the free passage of the oil. The plunger 12 fits within a stuffing-box nut 15, that has a forward-projecting annular flange 16, forming a guide for the outer portion of the plunger. The nut screws on the outer threaded end of the casing 6, and between the end of the case and the nut is a packing-ring 17, formed of yieldable material so arranged as to prevent the leakage of 80 oil around the exterior of the plunger, and this packing-ring, furthermore, forms a seat or cushion for checking outward movement of the plunger. The packing-ring receives the impact of the flange 13, and any oil that 85 may accumulate between the flange and ring is free to pass rearward through the notches 14 to the interior of the casing.

The hollow plunger 12 is provided at its outer end with a valve-seat for the reception 95 of a disk valve 18, the stem of which is guided within the bore of the plunger, and against the outer face of the valve presses a compression-

spring 19, that is held within a nozzle member 20, having a threaded connection with the end of the plunger 12.

Between the inner end of the casing 6 and 5 the similar end of the plunger 12 is a strong compression-spring 21, that normally tends to force the nozzle outward to the position illustrated in Fig. 1, and during this outward movement the pressure of oil in the casing will 10 open the valve 10 and the oil will flow freely to the interior of the casing and the hollow plunger, so that all parts will fill with oil when the nozzle is in the position shown. The nozzle is then applied inside against the oil-hole 15 in a wheel-hub or other point to be lubricated and pressure is applied for forcing the nozzle rearward, or the nozzle may remain stationary while the receptacle and all of the connected parts is moved forward. This pressure 20 serves to close the valve 10 and open the valve 18, the oil within the casing 6 and the hollow plunger being forced outward through the nozzle to the point to be lubricated. This operation may be repeated as often as necessary; but for ordinary purposes a single application 25 will suffice, and each part lubricated will therefore receive the same measured quantity of oil.

Having thus described the invention, what 30 is claimed is --

1. In a lubricating apparatus, an oil-receptacle, a casing projecting thereinto and having a valved inlet for the passage of the oil, a stuffing-box nut at the outer end of the casing, a hollow plunger guided by the casing and extending through the nut, a spring tending 35 to force the plunger outward from the casing, a spring-closed valve at the outer end of the plunger, and a chambered nozzle secured 40 to the end of the plunger the chamber serving to contain the closing-spring of the outer valve.

2. In a lubricator, an oil-receptacle, a casing secured thereto and having a valved inlet, a spring-pressed plunger arranged within the 45 casing and provided with a notched flange, a stuffing-box nut secured to the threaded end of the casing and having a forwardly-extended annular flange forming a guide for the plunger, a packing-ring held in place by the nut 50 and forming a cushion for engagement by the notched flange, a valve for closing the outlet from the plunger, and a nozzle member secured to the plunger and surrounding the valve.

3. In a lubricator, the combination with an oil-receptacle, of an internally-threaded flanged collar secured thereto, a casing having a threaded connection with the collar and provided at its inner end with a spring-closed inlet-valve, a hollow plunger guided within the casing and provided with a notched flange portion, a spring disposed between the inner ends of the casing and plunger and tending to force the latter outward, a stuffing-box nut 60 having a threaded connection with the outer portion of the casing and provided with a forwardly-extending annular flange serving as a guide for the plunger, a washer held in place by the nut and forming a cushion for engagement by the notched flange, an outlet-valve at the outlet end of the plunger, a nozzle member having a threaded connection with the outer end of the plunger and surrounding the valve, and a coiled compression-spring 65 arranged between the nozzle and the outlet-valve, substantially as specified.

In testimony that I claim the foregoing as my own I have hereto affixed my signature in the presence of two witnesses.

CHARLES JACOB GUSTAFSON.
